PROGRAMMABLE TESTER FOR TESTING
DIGITAL AND ANALOG CIRCUIT BOARDS
AND LOGIC CIRCUITS

John O. Pierce, County of Ventura, Calif., assignor to
Litton Systems, Inc., Beverly Hills, Calif.

Filed July 12, 1971, Ser. No. 161,412

Term of patent 14 years

Int. Cl. D10—05

U.S. Cl. D26—1 Q

Fig. 1

Fig. 2

Fig. 3

Fig. 4

Fig. 5

Fig. 6

FIG. 1 is a front perspective view of a programmable tester for testing digital and analog circuit boards and logic circuits;

FIG. 2 is a front elevational view thereof;

FIG. 3 is a rear elevational view thereof;

FIG. 4 is a right side elevational view thereof;

FIG. 5 is a left side elevational view thereof; and

FIG. 6 is a top plan view thereof.

FIG. 3 shows partially complete grillwork for air ventilation in the large rectangle and the small square in the lower center. FIG. 3 also shows two partially complete connectors for cable connection near the lower left corner. Partially complete grillwork and partially complete connectors are shown for purposes of ease of illustration.

I claim:

The ornamental design for a programmable tester for testing digital and analog circuit boards and logic circuits, as shown and described.
